UNITED STATES PATENT OFFICE.

HARRY M. PFLAGER, OF ST. LOUIS, MISSOURI, ASSIGNOR TO COMMONWEALTH STEEL COMPANY, OF GRANITE CITY, ILLINOIS, A CORPORATION OF NEW JERSEY.

LOCOMOTIVE CONSTRUCTION.

Application filed March 10, 1927. Serial No. 174,273.

My invention relates to railway rolling stock and consists in an improved construction of that part of the locomotive including and adjacent to the cross head guides.

5 The objects of my invention are to eliminate unnecessary fitting and alignment of separate guides and their supporting elements and the portion of the frame to which they are applied; to provide a structure 10 in which the spacing of the parts will be more accurately maintained and in which there will be no joints or fastening elements to loosen up and affect the functioning of the parts or the separation of the members 15 mounted thereon; and to provide means for renewing worn surfaces in the cross head guide structure.

I also desire to secure the above results and the maximum strength of the parts involved 20 with a minimum amount of metal. Briefly, my invention consists in forming the cross head guides integrally with their supporting elements and preferably by casting the guides and supporting elements with the locomotive 25 frame.

In the accompanying drawings which illustrate a selected embodiment of my invention—

Figure 1 is a side elevation of the front 30 end of a locomotive frame embodying my invention.

Figure 2 is a one-half longitudinal top view of the same structure.

Figures 3 and 4 are transverse vertical sections taken on lines 3—3 and 4—4, respectively, of Figure 1.

Figure 5 is a side elevation of a modified structure.

Figure 6 is a top view of the same.

40 Figure 7 is a transverse section taken on line 7—7 of Figure 5.

In the drawings, the locomotive frame or bed is indicated at 1 and is shown as a casting with pedestal jaws 2, steam cylinder 3, boiler saddle 4, and front deck plate 5, all formed 45 integrally. Spaced from the cylinder 3 is a yoke member 6 having suitable brackets 7 upon which the valve gear may be mounted and having brake hanger lugs 8 and a downward extension 9. Integral with the yoke member are the forwardly extending upper and lower cross head guides 10 and 11, respectively, the forward ends of which merge 50 with the rear end of cylinder 3. The guides 55 10 and 11 are preferably channel-shape in

cross section as best shown in Figure 3 and after being machined they have wear plates 12 applied thereto. These wear plates are preferably of channel-shape also, and are detachably secured to the guides so that they 60 may be readily removed and replaced when worn without affecting the finished surface of the guide members 10 and 11.

In the modification illustrated in Figures 5, 6, and 7 the forward ends of the cross head guides 13 are supported upon a bracket 14 formed integrally with the bed 15 and these cross head guides 13 are not united directly with the cylinder 16. With this construction the cylinder head 17 may be made 70 detachable from the cylinder in the ordinary manner and the head may be applied and removed without disturbing the cross head guides.

The bracket 14 also includes the brake hanger lugs 18, and the depending portion 19 of the bracket is located on the inside of the cross head guides, thus facilitating application and removal of the cylinder head.

Of course, this construction could be used 80 even though the cylinder head were formed integrally with the cylinder, and this construction is also adapted for use in a structure in which the cylinder is removable from the bed.

85 Any of the cross head guides indicated may be of solid rectangular cross section, of I-shaped cross section, or of any other desired shape, and it is not essential to the embodiment of my broad invention that there should 90 be upper and lower cross head guides as a single guide is sometimes used and could be cast integrally with the bracket or frame, or cylinder, or with any two or more of these elements, and could be provided with a renewable wear plate similarly to the two cross head guides illustrated.

95 My invention contemplates the forming of the cross head guides integrally with the brackets which may be applied as a unit to 100 the frame.

My invention may be further modified by forging various combinations of the parts integrally with each other instead of casting them in one piece as contemplated in the preferred embodiment of my invention.

I contemplate the exclusive use of all these and such other modifications of my invention as are included in the scope of my claims.

I claim:

110

1. A locomotive frame and a cross head guide formed integrally with each other.
  2. In locomotive structure, a steam cylinder, a valve gear bracket, and a cross head guide connecting said cylinder and bracket and cast integrally therewith.
  3. In a locomotive; a frame, a steam cylinder, a valve gear bracket, and a cross head guide, all of said parts being cast integrally.
  10. 4. A bracket for a locomotive valve gear and cross head guide, and a cross head guide formed integrally with said bracket.
  5. In a locomotive, a steam cylinder, a valve gear bracket, and vertically spaced horizontal cross head guides extending between said cylinder and bracket and formed integrally with the same and with each other.
  15. 6. A unitary structure for locomotives comprising a bracket extending from the locomotive frame, and cross head guides formed integrally with said bracket.
  20. 7. A unitary structure for locomotives comprising a bracket extending from the locomotive frame, a steam cylinder element extending from the locomotive frame, and cross head guides formed integrally with said bracket and element.
  25. 8. A one-piece casting comprising a locomotive frame and a cross head guide.
  30. 9. A one-piece casting comprising a locomotive frame and upper and lower cross head guides integrally connected exteriorly of said frame.
  35. 10. A one-piece casting comprising a locomotive frame, a cross head guide bracket and a cross head guide.
  40. 11. A one-piece casting comprising a locomotive frame, a cross head guide bracket, steam cylinder elements and a cross head guide.
  45. 12. In a locomotive, a one-piece casting including a steam cylinder element, a valve gear bracket and a cross head guide between said cylinder element and bracket, and a removable wear plate secured to said guide.
  50. 13. In a locomotive, a one-piece casting including a steam cylinder element, a bracket for a valve gear and cross head guide and a cross head guide between said cylinder element and bracket, and a removable wear plate secured to said guide.
  55. 14. In a locomotive, a frame, a bracket on said frame, upper and lower cross head guides extending forwardly of said bracket, and means for supporting the forward ends of said guides, said bracket, guides, and means being formed integrally with said frame.
  60. 15. In a locomotive, a frame, supports for a cross head guide spaced longitudinally of the frame and extending outwardly therefrom, and a cross head guide, all formed integrally.
  65. 16. In a locomotive, a side frame element including a cross head guide, and a renewable wear plate on said guide for mounting the cross head.
  70. 17. In a locomotive, a locomotive frame, a bracket thereon, a cross head guide supported by said bracket, said frame, bracket, and guide being formed integrally, and a renewable wear plate on said guide for mounting the cross head.
  75. 18. In combination, a locomotive frame, integral laterally projecting elements on said frame spaced longitudinally thereof, a cross head guide extending between said elements and formed integrally therewith, and a renewable wear plate detachably secured to said guide.
  80. 19. In combination, a bracket for a locomotive valve gear and cross head guide, a cross head guide formed integrally with said bracket, and a renewable wear plate mounted on said guide.
  85. 20. In combination, a locomotive cross head guide, a bracket for mounting the same on a frame member, said guide and bracket being formed integrally with each other, and a renewable wear plate mounted on said guide.
- 90
In testimony whereof I hereunto affix my signature this 7th day of March, 1927.

H. M. PFLAGER.
